AUTOMATIC DRAIN VALVE

Burton S. Aikman, Wilkinsburg, Pa., assignor to
The Westinghouse Air Brake Company, Wil-
merding, Pa., a corporation of Pennsylvania

Application August 14, 1936, Serial No. 96,009

11 Claims. (Cl. 303—88)

This invention relates to an automatic drain valve for use on a reservoir or receiver for fluid under pressure and which operates to release moisture from this receiver or reservoir.

5 In the operation of fluid pressure systems, such as fluid pressure brake systems, air from the atmosphere is compressed and is stored in a reservoir or receiver from which fluid is withdrawn during operation of the brake equipment. As a 10 result of the supply of fluid under pressure to and the release of fluid under pressure from the reservoir, water is deposited in the reservoir and unless it is periodically drained away it accumulates in the reservoir and reduces the volume of 15 the reservoir, while it may freeze and cause injury to the equipment.

It is an object of this invention to provide valve means adapted to be employed to release liquid which accumulates in the reservoir of a 20 fluid pressure system.

A further object of the invention is to provide a valve device automatically operable in response to variations in the pressure of the fluid in a reservoir or receiver for controlling a communication through which liquid may be released from 25 the reservoir or receiver.

Another object of the invention is to provide a valve device of the type described which releases fluid from the receiver in limited volumes 30 so that the supply of fluid in the receiver will not be unduly depleted by operation of the valve device.

A further object of the invention is to provide a valve device of the type described which is of 35 rugged construction, and in which the elements are of such design as not to be damaged if water present in the device freezes.

A further object of the invention is to provide an improved automatic drain valve device.

40 Other objects of the invention and features of novelty will be apparent from the following description taken in connection with the accompanying drawing, the single figure of which is a sectional view showing a drain valve device 45 embodying my invention.

Referring to the drawing, there is illustrated therein a portion of a receiver or reservoir 1 for a fluid pressure system which is supplied with fluid under pressure by a suitable compressor, not shown, and from which fluid is withdrawn 50 through a suitable pipe, not shown.

The drain valve device provided by my invention is mounted in a threaded opening in the lowermost portion of the reservoir or receiver 1, and, as 55 shown, comprises a hollow body 2 having tubu-

lar threaded portion 4 adapted to be received by the threaded opening in the reservoir 1.

The body 2 has an annular chamber 6 formed therein and the upper portion of this chamber is of larger cross-sectional area than the lower 5 portions thereof.

The body 2 has a tubular sleeve portion, indicated as 8, formed integral therewith and extending downwardly from the upper wall of the chamber 6 substantially to the face of the threaded plug 10 which closes the lower portion of the chamber 6. The plug 10 has a release passage 12 extending therethrough.

The tubular sleeve portion 8 has a bore therein in which is mounted a movable abutment or 15 element in the form of a piston 14 having a central boss thereon through which extends a passage in which is mounted a valve member 18 having a fluted stem 16. The valve member 18 is adapted to engage a seat formed on the piston 20 14 surrounding the upper end of the passage through the piston.

A spring 20 is provided and extends between the piston 14 and a spring seat 22 secured on the stem 16 of the valve 18 so as to yieldingly 25 press the valve 18 into engagement with its seat. The spring 20 is under slight initial compression so that it lightly presses the valve 18 against the piston 14 and so that a small force is required to unseat the valve 18. 30

The lower end of the stem 16 of the valve 18 has a substantially conical face thereon indicated at 24, which is adapted to seat upon a seat formed on the plug 10 surrounding the release passage 12. 35

In initially charging the equipment, fluid under pressure is supplied to the reservoir 1 and it exerts force on the upper face of the piston 14 to press the piston downwardly. On downward movement of the piston 14, the face 24 40 on the end of the stem 16 is pressed into engagement with the seat surrounding the release passage 12, so that on further downward movement of the piston 14, the spring 20 is compressed, while the piston 14 is moved relative to 45 the valve 18 so that the seat on the piston 14 is moved away from the valve 18.

When the piston 14 is moved relative to the valve 18, fluid under pressure from the reservoir 1 flows through the passage through the piston 50 14 to the chamber 6 to increase the pressure of the fluid in this chamber. On an increase in the pressure of the fluid in the chamber 6 to a predetermined value below that in the reservoir 1, the force exerted by the fluid under pressure in 55

the chamber 6, together with the force exerted by the spring 20 on the piston 14, overcomes the opposing force of the fluid under pressure in the reservoir 1 on the piston 14, and the piston is 5 thereupon moved upwardly until the seat on the piston engages the valve 18 to cut off the further supply of fluid under pressure from the reservoir 1 to the chamber 6.

After movement of the piston 14 into engagement with the valve 18, the pressure of the fluid in the chamber 6 continues to build up by leakage of fluid thereto from the reservoir 1 past the piston 14 until the pressure of the fluid in the chamber 6 is substantially at the pressure of 10 the fluid in the reservoir 1.

On this increase in the pressure of the fluid in the chamber 6, the valve 18 is held in the seated position by the spring 20, while the face 24 on the end of the stem 16 of the valve 18 is held in 20 engagement with the seat on the plug 10 surrounding the release passage 12 by the weight of the piston 14 and the valve 18 and by the fluid under pressure in the reservoir 1 acting on an area of the valve 18 equal to the area surrounded by the seat on the plug 10 which is engaged by the face 24.

Any liquid which accumulates in the reservoir 1 flows by gravity to the lower portion thereof, and through the passage in the tubular portion 4 of the drain valve device to the chamber at the 30 face of the piston 14.

On a subsequent reduction in the pressure of the fluid in the reservoir 1 as a result of the withdrawal of fluid therefrom, there is a reduction 35 in the force exerted by this fluid on the piston 14 in opposition to the opposing force of the fluid in the chamber 6, and the piston 14 is thereupon moved upwardly by the fluid under pressure in the chamber 6.

On this movement of the piston 14, the face 24 40 on the end of the stem 16 is lifted away from the seat surrounding the release passage 12 so as to release fluid from the chamber 6 and thereby reduce the pressure of the fluid in this chamber.

On a reduction in pressure of the fluid in the chamber 6 to a value equal to or slightly below 45 the pressure of the fluid in the reservoir 1, the fluid under pressure in the reservoir 1 moves the piston 14 downwardly so as to move the valve face 24 on the end of the stem 16 into engagement with the seat on the plug 10 surrounding the release passage 12 to cut off the release of fluid 50 from the chamber 6.

The volume of fluid released from the chamber 55 6 before the pressure of the fluid in this chamber is reduced to a value equal to or slightly below the pressure of the fluid in the reservoir 1 is relatively small because of the relatively small volume of the chamber 6.

On a subsequent increase in the pressure of the fluid in the reservoir 1 as a result of the supply 60 of fluid thereto by operation of the compressor, the pressure of the fluid in the reservoir will exceed the pressure of the fluid in the chamber 6 on the opposite face of the piston 14 and when the pressure of the fluid in the reservoir 1 has increased to a predetermined value above the pressure of the fluid in the chamber 6, the force 65 exerted on the piston 14 by this fluid will exceed the opposing force exerted on the piston 14 by the fluid in the chamber 6 by an amount sufficient to move the piston 14 downwardly against the opposing force of the spring 20, while the valve face 24 on the end of the stem 16 is pressed more 70

firmly into engagement with the seat surrounding the release passage 12.

On this movement of the piston 14, the seat on the piston is moved away from the valve 18 so as to permit liquid accumulated in the chamber 5 above the piston 14 to flow through the passage 10 through the piston 14 to the chamber 6 at the opposite face of this piston. This liquid will flow past the lower end of the tubular sleeve portion 8, and the level of the liquid in the chamber 6 will increase until the pressure of the fluid trapped in the upper portion of the chamber 6 is increased substantially to the pressure of the fluid in the reservoir 1.

On an increase in the pressure of the fluid in 15 the chamber 6 there is an increase in the force acting on the piston 14 in opposition to the force exerted thereon by the fluid under pressure in the reservoir 1, and when the pressure of the fluid in the chamber 6 is increased substantially 20 to the pressure of the fluid in the reservoir 1, the piston 14 will be moved upwardly by this fluid under pressure, assisted by the spring 20, until the seat on the piston 14 engages the valve 18 to cut off the flow of fluid from the reservoir 1 to 25 the chamber 6 through the passage controlled by the valve 18.

On movement of the piston 14 upwardly into engagement with the valve 18, the spring 20 is no longer effective to exert force on the piston 14 30 tending to move it upwardly, while the pressure of the fluid in the chamber 6 is thereafter increased by leakage of fluid from the reservoir 1 past the piston 14 until the pressure of the fluid in the chamber 6 is built up substantially to the 35 pressure of the fluid in the reservoir 1. The face 24 on the end of the stem 16 is held in engagement with the seat surrounding the release passage 12 by the weight of the piston 14 and the valve 18 so as to cut off the release of fluid from 40 the chamber 6.

On a subsequent reduction in the pressure of the fluid in the reservoir 1 to a predetermined value below the pressure of the fluid in the chamber 6, the force exerted by the fluid under 45 pressure in the reservoir 1 on the piston 14 is insufficient to hold this piston against the opposing force of the fluid under pressure in the chamber 6, and the piston 14 is thereupon moved upwardly in the bore in the tubular sleeve portion 8. 50 On this movement of the piston 14, the valve 18 is lifted so that the valve face 24 on the stem 16 is out of engagement with the seat surrounding the release passage 12 and the liquid in the lower portion of the chamber 6 is forced out through 55 the release passage 12 by the fluid under pressure trapped in the upper portion of the chamber 6.

After a predetermined amount of liquid is released from the chamber 6, the pressure of the fluid remaining in this chamber is insufficient 60 to maintain the piston 14 against the opposing force of the fluid under pressure in the reservoir 1, and the piston 14 is thereupon moved downwardly by the fluid under pressure in the reservoir 1 until the valve face 24 on the end of the stem 16 engages the seat surrounding the passage 12 so as to cut off the further release of fluid 65 from the chamber 6.

On a subsequent increase in the pressure of the fluid in the reservoir 1, the piston 14 is moved 70 downwardly against the spring 20 so as to permit liquid which has accumulated in the chamber at the upper face of the piston 14 to flow therefrom through the passage in the piston 14 to the chamber 6 to increase the pressure of the fluid in this 75

chamber substantially to the pressure of the fluid in the reservoir 1, and the piston 14 is thereafter again moved upwardly until the seat thereon engages the valve 18.

5 On the next reduction in the pressure of the fluid in the reservoir 1, the drain valve device operates as described in detail above to again release liquid from the chamber 6, and this cycle of operation is repeated on subsequent fluctuations 10 in the pressure of the fluid in the reservoir 1.

It will be seen that the volume of fluid, either liquid or gaseous, released by the drain valve device on each fluctuation of the pressure of the fluid in the reservoir 1 is relatively small so 15 that the fluid under pressure in the reservoir 1 will not be unduly depleted by operation of the drain valve device. The amount discharged by the drain valve device on each operation thereof is, however, proportioned so that the drain valve 20 device is enabled to maintain the reservoir 1 substantially free from moisture.

It will be seen also that the chamber 6 in the body 2 of the drain valve device has a curved outer wall which increases in diameter away 25 from the bottom wall of the chamber, and that this chamber is only partially filled with liquid. As a result, if the liquid in this chamber should freeze, the ice which is formed will not adhere to the inner face of the wall of the chamber 30 6 so as to cause such pressure to be developed as would result in injury to portions of the valve device, or fracture the housing of the device.

It will be seen in addition, that this drain valve device operates automatically in response 35 to variations in the pressure of the fluid in reservoir 1, and that it requires no attention on the part of the operator of the fluid pressure system with which it is associated.

While one embodiment of the improved automatic drain valve device provided by my invention has been illustrated and described in detail, it should be understood that the invention is not limited to these details of construction, and that numerous changes and modifications may be 45 made without departing from the scope of the following claims.

Having now described my invention, what I claim as new and desire to secure by Letters Patent, is:

50 1. In a drain valve device for a reservoir, a body having a chamber therein, a movable element subject to the opposing pressures of the fluid in said reservoir and of the fluid in said chamber, and valve means operated by said element for controlling communication from the reservoir to said chamber and for also controlling communication from said chamber to the atmosphere.

2. In a drain valve device for a reservoir, a 60 body having a chamber therein, a movable element subject to the opposing pressures of the fluid in said reservoir and of the fluid in said chamber, and valve means operated by said element for controlling the flow of fluid from the reservoir to said chamber, and for also controlling the release of fluid from said chamber.

3. In a drain valve device for a reservoir, a 70 body having a chamber therein, a movable element subject to the opposing pressures of the fluid in said reservoir and of the fluid in said chamber, and a valve associated with said element, said valve being movable relative to the element by movement of the element for controlling communication between the reservoir 75 and said chamber, and being movable with said

element for controlling the release of fluid from said chamber.

4. In a drain valve device for a reservoir, a body having a chamber therein, a movable element subject to the opposing pressures of the fluid in said reservoir and of the fluid in said chamber, a valve associated with said element, said valve being movable relative to the element by movement of the element for controlling communication between the reservoir and said chamber, and being movable with said element for controlling the release of fluid from said chamber, and means yieldingly opposing relative movement between said valve and said element. 10

5. In a drain valve device for a reservoir, in combination, a body having a chamber therein and having a release passage surrounded by a seat communicating with said chamber, a movable element subject to the opposing pressures of the fluid in the reservoir and in said chamber, 15 said element having a passage therethrough surrounded by a seat, and a valve member having valve faces thereon adapted to engage the seats on said body and on said element.

6. In a drain valve device for a reservoir, in combination, a body having a chamber therein and having a release passage surrounded by a seat communicating with said chamber, a movable element subject to the opposing pressures of the fluid in the reservoir and in said chamber, 20 said element having a passage therethrough surrounded by a seat, a valve member having faces thereon adapted to engage the seats on said body and on said element, and means yieldingly urging a face on said valve member into engagement 25 with the seat on said element. 30

7. In a drain valve device for a reservoir, in combination, a body having a chamber therein and having a release passage surrounded by a seat communicating with said chamber, a movable element subject to the opposing pressures of the fluid in the reservoir and in said chamber, 35 said element having a passage therethrough surrounded by a seat, a valve member carried by said element and having a face thereon adapted to engage the seat on said element, said valve member having another face thereon adapted to engage the seat on the body. 40

8. In a drain valve device for a reservoir, in combination, a body having a chamber therein and having a release passage surrounded by a seat communicating with said chamber, a movable element subject to the opposing pressures of the fluid in the reservoir and in said chamber, 45 said element having a passage therethrough surrounded by a seat, a valve member carried by said element and having a face thereon adapted to engage the seat on said element, said valve member having another face thereon adapted to engage the seat on the body, and means yieldingly urging said valve member into engagement with the seat on said element. 50

9. In a drain valve device for a reservoir, in combination, a body having a chamber therein having a passage adapted to communicate with said reservoir, said passage opening into said chamber at the lower portion thereof, means subject to the opposing pressures of the fluid in said chamber and of the fluid in the reservoir and operative on an increase in the pressure of the 70 fluid in the reservoir to open a communication through which water accumulated in the reservoir may drain from the reservoir through said passage to said chamber and through which fluid under pressure may be supplied to said chamber, 75

and means operated on a reduction in the pressure of the fluid in the reservoir to open a communication through which water present in said chamber may drain therefrom.

- 5 10. In a drain valve device for a reservoir, in combination, a body having a substantially vertically extending bore therein, said body having a chamber associated therewith adapted to contain fluid under pressure and also having a communication between the lower portion of said bore and the lowermost portion of said chamber, a piston reciprocable in said bore, said piston being subject on one side to the pressure of the fluid in the reservoir and subject on the other 10 side to the pressure of the fluid in said chamber, valve means operable on an increase in the pressure of the fluid in the reservoir to a value exceeding the pressure of the fluid in said chamber to open a communication through which liquid accumulated in said reservoir may drain to said chamber through said communication and through which fluid under pressure may be supplied to said chamber, and valve means operated by said piston on a reduction in the pressure of the fluid in the reservoir to a value below the pressure of the fluid in the chamber to open a 15

communication through which liquid may drain from said chamber.

11. In a drain valve device for a reservoir, in combination, a body having a substantially vertically extending bore therein, said body having a chamber therein adapted to contain fluid under pressure and also having a communication between the lower portion of said bore and the lower portion of said chamber, a piston reciprocable in said bore, said piston being subject on one side to the pressure of the fluid in the reservoir and subject on the other side to the pressure of the fluid in said chamber, valve means operated by said piston on an increase in the pressure of the fluid in the reservoir to a value exceeding the pressure of the fluid in said chamber to open a communication through which liquid accumulated in said reservoir may drain to said chamber through said communication and through which fluid under pressure may be supplied to said chamber, and valve means operated by said piston on a reduction in the pressure of the fluid in the reservoir to a value below the pressure of the fluid in the chamber to open a communication through which liquid may drain from said chamber. 20 25

BURTON S. AIKMAN.
